CLAIM

The ornamental design for a hand-held housing for an electronic device, as shown.

DESCRIPTION

FIG. 1 is a perspective view from above of a hand-held housing for an electronic device showing a first embodiment of the design.

FIG. 2 is a perspective view from below of the hand-held housing for an electronic device shown in FIG. 1.

FIG. 3 is a top view of the hand-held housing for an electronic device shown in FIG. 1.

FIG. 4 is a bottom view of the hand-held housing for an electronic device shown in FIG. 1.

FIG. 5 is a right side view of the hand-held housing for an electronic device shown in FIG. 1, the left side view being a mirror image of the right side view.

FIG. 6 is a front end view of the hand-held housing for an electronic device shown in FIG. 1, the back end view being a mirror image of the front end view.

FIG. 7 is a perspective view from above of a hand-held housing for an electronic device showing a second embodiment of the design.

FIG. 8 is a perspective view from below of the hand-held housing for an electronic device shown in FIG. 7.

FIG. 9 is a top view of the hand-held housing for an electronic device shown in FIG. 7.

FIG. 10 is a bottom view of the hand-held housing for an electronic device shown in FIG. 7.

FIG. 11 is a right side view of the hand-held housing for an electronic device shown in FIG. 7, the left side view being a mirror image of the right side view; and,

FIG. 12 is a front end view of the hand-held housing for an electronic device shown in FIG. 7, the back end view being a mirror image of the front end view.
